UNITED STATES PATENT OFFICE

2,422,876

LAMINATED ABRASIVE TOOL

George W. Allred, Mayodan, N. C.

Application January 5, 1945, Serial No. 571,418

7 Claims. (Cl. 51—190)

1

This invention relates to abrasive tools of the type in which a strip of flexible sheet material carrying abrasive grains on its surface is wound a plurality of turns to form a cylindrical wheel which may be supported upon and rotated by an arbor or a belt which may be supported upon and rotated by a plurality of rolls. The invention is applicable also to abrasive discs and other abrasive devices in which a plurality of layers of flexible abrasive are secured together.

In my Patent No. 2,363,739, I disclosed an abrasive wheel formed by gluing non-abrasive strips at the edges of the back of the abrasive sheet and securing the turns of the abrasive sheet together by gluing together the free edges of the non-abrasive strips. This construction has the advantages that the turns of the abrasive strip are held together without applying adhesive to the abrasive surfaces and the resulting tool has a very desirable flexibility or softness due to the fact that the non-abrasive strips slightly space apart the successive turns of the abrasive sheet.

An object of the present invention is to provide abrasive tools formed of a plurality of turns or layers of abrasive sheet in which the use of non-abrasive strips glued to the edges of the abrasive sheet, as described in said patent, is avoided.

A preferred embodiment of my present invention consists in an abrasive tool formed by superposing a plurality of layers of flexible sheet material having an integral edge portion or border which is not coated with abrasive, the flexible sheet material or at least that portion thereof which is coated with abrasive being yielding or resilient. It is within the scope of my invention however to omit the resilient feature of the flexible support and to use paper or cloth such as commonly is used for sandpaper, emery cloth and the like.

The invention is illustrated in the accompanying drawings in which

Fig. 1 is a front elevation of an abrasive wheel with a portion broken away to reveal a section thereof;

Fig. 2 is a front elevation of an abrasive belt;

Fig. 3 is a plan view of the abrasive strip with integral non-abrasive edge portions;

Fig. 4 is a plan view of an abrasive strip with the non-abrasive edge notched to facilitate bending;

Fig. 5 is a plan view of an abrasive strip with the non-abrasive edge merely cut to facilitate bending;

Fig. 6 is a section of an abrasive tool showing

one method of employing the integral non-abrasive edge portion of the strip for binding successive layers together; and

Fig. 7 is a section of an abrasive tool showing another method of using the integral non-abrasive edge portion for binding the layers together.

The strip of abrasive sheet comprises a layer of abrasive material such as sand, emery or the like secured to a flexible support such as paper, cloth or the like by means of glue or other suitable adhesive. In accordance with the invention, the support may be soft, compressible and resilient such as cloth, having one side knapped, or felt or a thick soft paper like blotting paper which preferably has, as is common in blotting paper, a relatively hard and compact surface layer to which the abrasive material is attached and a soft, compressible and resilient base layer.

In accordance with my invention, the flexible support for the abrasive, whether said support is soft and resilient or ordinary paper or cloth such as commonly is used in making sand and emery paper, has an integral edge portion or border which is not coated with abrasive and which is used for binding the layers of abrasive sheet together. When the flexible support is soft and resilient, the non-abrasive edge portion thereof also may be soft and resilient or this edge portion may be relatively hard and non-resilient like ordinary paper or cloth. Thus the edge portion may be left unknapped or the edge only of the soft resilient sheet may be compressed to a relatively thin, hard compact layer or as in the case of paper having a hard, compact front layer and a soft, compressible and resilient base layer, the latter may be omitted or removed at the edge portions.

The edge portion of the abrasive sheet may be plain as shown in Fig. 3 or notched as shown in Fig. 4, or merely cut as shown in Fig. 5 and, as is apparent, the non-abrasive edge portion shown in Fig. 3 may be as wide or narrow as desired, the notches in the edge portion of Fig. 4 may be of any desired shape and distribution and the slits or cuts in the edge portion, Fig. 5, may be at right angle to the axis of the strip or at any other suitable angle.

It is to be understood that the abrasive strips illustrated in Figs. 3, 4 and 5 may consist of a layer of abrasive on a flexible support, the entire width of which is ordinary non-resilient paper or fabric or the entire width of which is soft and resilient or that portion which is coated with abrasive material may be resilient and the non-abrasive edge portions non-resilient.

The particular structures illustrated in Figs. 6

and 7, will be described in the following detailed description of the drawings.

Referring to Fig. 1, 1 is an abrasive wheel formed by winding the abrasive strip 2 around the core 3 carried on the arbor 4. The abrasive strip 2 consists of the layer of abrasive grains 6 and the flexible backing 5. The edges 7 of the abrasive strip are free of abrasive grains and are bent together and secured by adhesive. The resulting rough end surface of the wheel is covered and finished by the disc 8 which is secured in place by adhesive.

Fig. 2 shows the belt 9 made of a plurality of turns of flexible abrasive sheet, carried on the rollers 10, 10. The upper span of the belt where pressure is applied in the use of the belt is backed by the bed plate 11.

In Fig. 3, the non-abrasive edges 7 of the abrasive strip are integral and whole, while Fig. 4 shows the non-abrasive edges provided with suitably shaped and spaced notches 12, and Fig. 5 shows the non-abrasive edges provided with suitably spaced and directed cuts 13. It will be understood that the abrasive strips illustrated in Figs. 3, 4 and 5 may be resilient or non-resilient in both the abrasive coated and edge portions, or resilient in the abrasive coated and non-resilient in the edge portion. It will be understood further that any of the strips illustrated in Figs. 3, 4 and 5 may be employed in the construction of the tools illustrated in Figs. 1 and 2.

In Fig. 6, I have illustrated a tool construction in which the non-abrasive integral edges 7 of the abrasive strip are of a width substantially equal to the width of the abrasive portion of the strip and are turned back over the abrasive layer so as to form a covering therefor and a means for attachment to the non-abrasive face of the next layer or turn of abrasive strip. As illustrated in Fig. 6, the non-abrasive edges of the top layer of abrasive sheet have been removed to expose the abrasive surface, but the edges 7 of the second layer are turned in and glued to the back of the top layer and the edges 7 of the third layer are turned in and glued to the back of the second layer, and so on. In this construction the layers are not held together by glue applied to the abrasive surface but by glue applied to the non-abrasive edges of the abrasive strip and to the back of the abrasive portion of the strip. In this construction, the whole abrasive strip including the non-abrasive edges may be made of ordinary non-resilient paper or fabric, or the whole strip may be made of resilient flexible sheet such as knapped fabric or felt or soft paper such as blotting paper, or the abrasive portion of the strip may be resilient and the non-abrasive edges non-resilient, and the edges may be whole as illustrated in Fig. 3 or notched as in Fig. 4, or cut as illustrated in Fig. 5. The resulting tool, even if the entire strip is non-resilient will be somewhat cushioned due to the presence between the abrasive layers of the layer formed by the edges 7. This cushioning effect may be amplified by making either the edges or the abrasive portion of the backing or both of resilient sheet material and/or by providing the edges 7 with perforations 14 as shown in Fig. 7.

It will be evident that the construction shown in Fig. 6 may be used in a wheel, belt, disc or any other abrasive tool made up of a plurality of layers of abrasive sheet and it will also be evident that instead of simply tearing off the non-abrasive edges of the top layer, they may be folded back against the edge or end of the tool and if

desired glued thereto to serve as a covering like the disc 8 of Fig. 1. It will be understood further that the tool illustrated may be provided with a separate end disc 8, as in Fig. 1, glued to the layers of abrasive sheet to hold them together, and that the gluing of the inturned edges 7 of one layer to the back of the next layer may, in that case, be omitted, and the inturned edges then serving merely to provide the desired cushioning of the tool.

Fig. 7 shows another method of using the non-abrasive edges of the abrasive sheet to bind the turns or layers together and if desired to provide a cushioned tool. In the tool construction illustrated in this figure, the non-abrasive edges are bent back and folded under the abrasive portion of the strip to contact with the abrasive surface of the next layer, but a portion of each non-abrasive edge is used to form the protruding loops or folds which are bent into contact and glued together at 15 to hold the layers of the abrasive tool together. The abrasive strip may be resilient or non-resilient, or the abrasive portion resilient and the non-abrasive portion non-resilient and the edges 7 may be whole or notched or cut as illustrated in Figs. 3 to 5, and the tool may be provided with an end disc like the disc 8 of Fig. 1 to hold the turns together.

I claim:

1. An abrasive tool comprising a plurality of superposed layers of sheet material, each layer comprising a portion coated with abrasive and uncoated portions, said uncoated portions being folded between adjacent layers of said coated portions and said layers being secured together by adhesive attachment between uncoated surfaces thereof.

2. An abrasive tool as defined in claim 1 in which the non-abrasive portion of each layer excepting the top layer is folded over the abrasive surface of the abrasive coated portion thereof between said abrasive surface and the non-abrasive surface of the abrasive coated portion of the next layer.

3. An abrasive tool as defined in claim 1 in which the non-abrasive portion of each layer is folded against the non-abrasive surface of the abrasive coated portion thereof between said non-abrasive surface and the abrasive surface of the next layer.

4. An abrasive tool as defined in claim 1 in which the non-abrasive portion of each layer is folded along a line adjacent to but spaced apart from the edge of the abrasive coated portion to lie partially between the abrasive coated portion thereof and the abrasive coated portion of the next layer with the folded part of said non-abrasive portion adjacent said line lying outside the area of superposed abrasive coated portions of said layers.

5. An abrasive tool as defined in claim 1 in which the non-abrasive portion of each layer excepting the top layer is folded over the abrasive surface of the abrasive coated portion thereof between said abrasive surface and the non-abrasive surface of the abrasive coated portion of the next layer, and the non-abrasive portion of each layer is adhesively attached to the non-abrasive surface of the abrasive coated portion of the next layer.

6. An abrasive tool as defined in claim 1 in which the non-abrasive portion of each layer is folded along a line adjacent to but spaced apart from the edge of the abrasive coated portion to lie partially between the abrasive coated portion

thereof and the abrasive coated portion of the next layer with the folded part of said non-abrasive portion adjacent said line lying outside the area of superposed abrasive coated portions of said layers, and the protruding parts of the non-abrasive portions adhesively attached to each other.

7. An abrasive tool as defined in claim 1 in which the non-abrasive portions of at least part of the layers are folded between the successive 10 layers of the abrasive coated portions thereof and said non-abrasive portions are perforated to impart softness and resilience thereto.
